UNITED STATES PATENT OFFICE.

MELANCTON B. BRISTOL AND ORANGE A. PAGE, OF OSKALOOSA, IOWA.

WINDOW BLIND OR SHUTTER.

SPECIFICATION forming part of Letters Patent No. 309,024, dated December 9, 1884.

Application filed October 6, 1884. (No model.)

To all whom it may concern:

Be it known that we, M. B. BRISTOL and ORANGE A. PAGE, citizens of the United States, residing at Oskaloosa, in the county of 5 Mahaska and State of Iowa, have invented certain new and useful Improvements in Inside Window Blinds or Shutters, of which the following is a specification, reference being had to the accompanying drawings.

10 This invention has relation to improvements in inside window blinds or shutters; and it consists in the peculiar construction and novel arrangement of the slats, and, in combination therewith, of the frame having grooves to receive the said slats, all as will be hereinafter more fully set forth, and particularly pointed out in the claims appended.

15

In the accompanying drawings, to which similar letters of reference are made indicating 20 corresponding parts in the several figures, Figure 1 is a view of a section of a window-blind constructed according to our improvements. Fig. 2 is a vertical central sectional view of a portion of the same. Fig. 3 is an 25 end view of several of the slats, showing the same connected to each other. Fig. 4 is a detail sectional view of the frame, and Fig. 5 is a perspective view of one of the slats.

Referring to the said drawings by letter, A 30 indicates the frame, which may be of any ordinary or approved construction, having the rails *a* respectively provided on their inner sides with longitudinal grooves *b* for the reception of the slats, as will be presently explained.

B indicates the slats, which are of a peculiar construction, having their opposite edges grooved or recessed longitudinally, as at *c*. One of the walls of each of these respective 40 recesses terminates in an acute angle with relation to the flat or beveled outer side thereof, as at D, and the opposite wall at an abrupt or obtuse angle, as at E, the acute-angled wall of the groove being designed to engage the adjacent 45 grooves of the slat, respectively, and the abrupt-angle wall designed to overlap the outer side of the slats, as shown at F. The walls *E* are of much greater depth than the walls *D*, the object of which is to provide for shrinkage and prevent the slats from drawing apart, 50 so as to create an opening which would cause the admission of light. The opposite ends of

these slats are tenoned or recessed obliquely on opposite sides for their insertion into the slots of the rails *a* of the frame. These recesses are of a form substantially as shown in Figs. 3 and 5, being thicker at the opposite longitudinal or overlapping edges on opposite sides, and tapering in the direction of each other toward the acute-angle wall of the 60 groove, the shoulders *d* of the tenons engaging snugly the inner plane sides of the respective rails of the said frame. Thus it will be perceived that the advantages of both a lap-slat and tongue-and-groove slat may be 65 obtained in a single slat, which can be manufactured as cheap as the slats at present in use. These slats, in connection with the bars having the longitudinal grooves, form a very durable blind, and may be applied to rolling 70 blinds as well as fixed or stationary ones.

What we claim as new, and desire to secure by Letters Patent, is—

1. The combination, in a window blind or shutter, of the side rails provided with longitudinal grooves, and the slats having their longitudinal edges respectively grooved and their ends tenoned to engage the grooves of the said rails, the tenons being oblique to the sides of the slats, and one of the edge walls of 80 each slat-groove adapted to engage the groove of the adjacent slat, and its opposite wall overlap the same, substantially as specified.

2. A window-slat having its ends tenoned obliquely to its sides and its opposite longitudinal edges recessed, so as to present an acute and an obtuse edge wall on each respective longitudinal edge of the slat, whereby the acute-angle edge of each slat may be received by the edge recess of the adjacent slat, and the 85 obtuse-angle edge brought to overlap the adjacent acute-angle wall of the recess throughout the blind, substantially as shown and described.

3. The combination, with the side rails of a window blind or shutter having longitudinal grooves, of the slats having their ends tenoned to engage the said grooves, and their longitudinal edges grooved throughout their length, one of the edge walls of each recess being adapted to fit within the longitudinal edge recess of the adjacent slat, and the opposite wall of the same recess adapted to overlap the outer side of the same slat, whereby both a lap and a

tongue-and-groove joint may be formed, substantially as specified.

4. A window-slat having its ends tenoned for insertion into the grooved rails of a window-frame, and grooved on opposite longitudinal edges, respectively, with one wall of each groove of less length than the other, substantially as specified.

5. A window-slat having its ends tenoned obliquely to its sides, and grooved longitudinally on opposite edges, having one of the walls of

each groove of less length than the other, and terminating in an acute angle, substantially as shown and described.

In testimony whereof we affix our signatures ¹⁵ in presence of two witnesses.
